CONTROL SYSTEM FOR TRACK SWITCHES

Wade H. Reichard, Rochester, N. Y., assignor to
General Railway Signal Company, Rochester,
N. Y.

Application June 30, 1930, Serial No. 464,903

4 Claims. (Cl. 246—138)

This invention relates to systems employed for the control of railway track switches, and more particularly pertains to an alternating current system of this type having inherent characteristics protecting it from crosses, grounds and the like.

One object of this invention, is to provide a system having the above mentioned cross protection characteristics which is entirely operable upon alternating current.

Other objects, purposes and characteristic features of the present invention will be in part obvious from the accompanying drawing, and in part pointed out as the description of the invention progresses.

In describing the invention in detail, reference will be made to the accompanying drawing, in which the apparatus and circuit arrangement employed for the control of a railway track switch in accordance with the present invention has been shown in a diagrammatic manner.

With reference to the accompanying drawing, a main track has been illustrated by the rails 5, and a diverging route has been illustrated by the rails 6, this diverging route being connected to the main track by a track switch TS.

The track switch TS is operated to either a normal locked position, as shown, or to a reverse locked position by a suitable switch machine SM, such for example, as shown in the patent to W. K. Howe, Patent No. 1,466,903, dated September 4, 1923, with an alternating current motor and control means adapted thereto, as herein described in accordance with the present invention.

Besides the operating mechanism of the switch machine as disclosed in the above mentioned patent, this switch machine SM includes an alternating current induction motor M of the two phase winding type having a rotor or armature A and two phase windings PH¹ and PH². Associated with the motor M is a condenser C of suitable capacity to provide the desirable relative phase displacement between the currents in the respective phase windings PH¹ and PH² when the motor M is receiving operating current.

The switch machine SM also includes a group of pole changer contacts PC and an electromagnetic brake BR.

The pole changer contacts PC include movable contacts 7, 8 and 9. The movable contact 7 makes contact between a certain pair of fixed contacts when in a normal extreme position, and a certain other pair of fixed contacts when in a reverse extreme position. This movable contact 7 is mechanically operated by the switch machine to its respective positions in correspondence with the position of the track switch TS at the end of each operation; or is electrically operated to the opposite position during the operation of the switch machine to thereby reverse the switch ma-

chine in mid-stroke. This electric operation of the movable contact 7 during the operation of the switch machine is provided for by a pole changer coil 12 for operating the movable contact to a normal extreme position and a pole changer coil 14 for operating the movable contact to a reverse extreme position.

The movable contacts 8 and 9 are capable of assuming normal positions, intermediate positions and reverse positions. These contacts are operated to intermediate positions as soon as the track switch TS is unlocked by the switch machine SM; and are operated to extreme positions in correspondence with the track switch TS as soon as the track switch is again locked. However, these contacts when operated to extreme positions are preferably caused to be actuated slightly prior to the movement of the movable contact 7 for reasons hereinafter pointed out.

The brake BR, may be of any suitable type, such as shown for example, in the patent to W. K. Howe, Patent No. 1,852,574 dated April 5, 1932, which is operably released by the operating current, as it is connected in series with the two phase windings PH¹ and PH². When the brake is released, the armature A can then operate the switch machine.

A control relay CR is provided at the track switch TS to govern the operation of the switch machine SM. This control relay CR is of the alternating current induction type, such for example as shown in the patent to W. K. Howe, Patent No. 1,710,664, dated April 23, 1929, having a rotor CR and two phase windings 15 and 16. The rotor CR operates the contacts 18 and 19 to either of two extreme positions depending upon the energization of the two phase windings 15 and 16 as hereinafter explained. The windings 15 and 16 are constructed alike and therefore have substantially the same electrical characteristics. They are mounted on a magnetic structure such as used in a polyphase induction type relay, as shown in the above mentioned Patent 1,710,664.

Associated with the relay CR are two asymmetric units R¹ and R² which are connected in series combinations with their respective phase windings 15 and 16. These two asymmetric units are oppositely poled in respect to each other. These series combinations are connected in multiple as illustrated and are controlled over the line circuit extending to the tower in a manner hereinafter described.

The relay CR may, in some cases, be provided with a toggle arrangement or other means for holding its contacts 18 and 19 in their last operated positions should the relay CR become de-energized in such emergency cases as that of power failure or the like.

In a tower located at some convenient point, a

control lever L is provided, which is slideable back and forth to operate contact blocks 20 and 21 to either of two extreme positions. When these movable contact blocks 20 and 21 are in one extreme position, they make contact between certain respective pairs of fixed contacts, and when in the opposite extreme position make contact between certain other respective pairs of fixed contacts. Also, an asymmetric unit R³ is associated with the lever L.

A source of alternating current potential is provided both at the tower and at the switch location, which source is specifically illustrated as a suitable transmission line extending between the two points. In the tower a local transformer T¹ is provided to supply alternating current energy from the transmission line at that point through two fuses 2 and 23, while at the track switch a local transformer T² is provided to supply electrical energy from the transmission line at that point through two fuses 24 and 25.

The asymmetric units R¹, R² and R³ are preferably of either the electrolytic, crystal or copper oxide type in which the direction of rectification is inherent in accordance with the chemical action or physical phenomena inherent in its construction. Also, these rectifying units are preferably of the type which allow a certain amount of leakage or back flow current therethrough for purposes hereinafter explained.

It is believed that the various functions and features of the invention will be best understood by further description being set forth from the standpoint of operation.

35

Operation

With the control lever L in the normal extreme position shown, two energizing circuits receiving energy from the local transformer T¹ are completed for the relay CR over the line circuits extending from the tower, which causes the contacts 18 and 19 to assume extreme positions, such for example as those shown.

The first energizing circuit is traced from the left-hand terminal of the secondary of transformer T¹, through fuse 22, wires 30 and 31, contacts 32—20, wire 33, rectifying unit R³, wire 34, contacts 35—21, line wire 36, wire 37, rectifying unit R¹, phase winding 15 of relay CR, line wire 38, fuse 23, back to the right-hand terminal of the secondary of transformer T¹.

The second energizing circuit is traced from the left-hand terminal of the secondary of transformer T¹, through fuse 22, wires 30 and 31, contacts 32—20, wire 33, rectifying unit R³, wire 34, contacts 35—21, line wire 36, wire 39, rectifying unit R², phase winding 16 of relay CR, line wire 38, fuse 23, back to the right-hand terminal of the secondary of transformer T¹.

It will be noted, that the first energizing circuit for the relay CR has the rectifier units R¹ and R³ connected in series therein in a manner so that their valve actions are in the same direction in the circuit, thus causing a uni-directional pulsating current of appreciable value to flow therein. As this circuit is of comparatively low resistance, this pulsating current will lag appreciably behind the impressed voltage as applied by the secondary of transformer T¹, by reason of the inductance of the phase winding 15.

In the second energizing circuit of the relay CR, the rectifying units R² and R³ are included therein with their respective valve actions opposing each other, so that the result in the circuit is exactly the same as a comparatively high resist-

ance included therein. Thus, an alternating current of considerably smaller value than the pulsating uni-directional current flowing in the phase winding 15 will flow in the phase winding 16 by reason of the high resistance of the circuit. This comparatively high resistance in the circuit causes this alternating current flow to be substantially in phase with the impressed voltage as supplied by the secondary of transformer T¹.

From the foregoing description, it is obvious that with the two types or kinds of current in the respective phase windings of the polyphase induction type relay, a torque will be produced in the rotor of such relay by reason of the phase displacement between the two kinds of current which will operate the contacts 18 and 19 to the positions as shown.

When the control lever L is moved to its opposite or reverse extreme position from that shown, two other energizing circuits are completed for the relay CR.

In one of these circuits the valve action of the rectifying units R² and R³ is in the same direction, thereby, in this case causing the unidirectional pulsating current to flow in the phase winding 16. However, in the other one of these circuits, the valve action of the rectifying units R¹ and R³ oppose each other thereby causing a relatively small alternating current to flow in the phase winding 15.

From this it is seen, that the phase windings 15 and 16 are respectively energized with the opposite types of current, thus changing the relative phase displacement of the currents in the two windings. This change in the relative phase relationship causes the contacts 18 and 19 to be operated to their opposite

extreme positions from those shown in the drawing.

With the control lever L in the normal extreme position, as illustrated, contacts 18 and 19 of relay CR are moved to extreme positions as shown. However, when the control lever L is moved to its opposite or reverse extreme position, the contacts 18 and 19 are operated to their opposite positions to correspond therewith and the switch machine SM receives operating current from the secondary of transformer T².

Assuming such reverse positions of lever L and contacts 18 and 19, the switch machine motor M is energized through a circuit from the left-hand terminal of the secondary of transformer T², through fuse 24, wire 40, contact 18 of relay CR

in a left-hand position, wires 41, 42 and 43, contacts 44—7, wire 45, phase winding PH¹, wire 46, winding of electro-magnetic brake BR, wires 47 and 48, fuse 25, back to the right-hand terminal of the transformer T².

This circuit energizes the phase winding PH¹ and the brake BR. Because this circuit is of comparatively low resistance and includes the phase winding PH¹ having inductive reactance, the current therein lags its impressed voltage from the secondary of transformer T².

In multiple with the phase winding PH¹ is the condenser C and phase winding PH², receiving current at the same time from the secondary of transformer T² through a circuit from wire 45, through wire 50, condenser C, wire 51, phase winding PH², to wire 46. The condenser C, included in this latter circuit, counteracts the inductive reactance of winding PH² and, therefore,

the current leads in time phase the current passing through winding PH¹. Due to the time phase difference of the currents through PH¹ and PH², the motor develops armature torque. The current which flows in this latter circuit combines with the current flowing in the circuit formerly

traced through the phase winding PH^1 , and flows through the winding of the electro-magnetic brake BR . The resultant current flowing in the brake BR is effective to actuate its braking element in a manner to release the armature A and allow it to operate the switch machine SM . This operation of the switch machine unlocks the track switch TS and operates the movable switch points thereof toward the reverse extreme positions.

Slightly before the track switch TS is unlocked, the movable contacts 8 and 9 are moved to intermediate positions, engaging their respective contacts 54 and 59, and with lever L and contacts 18 and 19 in their reverse positions, the pole changer coil 12 is energized through a circuit from the left-hand terminal of the secondary of transformer T^2 , through fuse 24, wire 40, contact 18 of relay CR in its left-hand position, wires 41 and 42, contacts 54—8, wire 55, pole changer coil 12 wires 56 and 48, fuse 25, back to the right hand terminal of the secondary of transformer T^2 . This energization of the pole changer coil 12 causes the movable contact 7 to be held in the normal position shown, during the time that the switch machine is operating the track switch TS towards its reverse position.

With the movable contact 9 in an intermediate position, the pole changer coil 14 is connected to the normal operating wire 58 of the switch machine in such a manner that it may be energized if the contacts 18 and 19 of the relay CR are returned to normal positions shown. This circuit is traced from the left-hand terminal of the secondary of transformer T^2 , through fuse 24, wire 40, contact 18 of relay CR in a right-hand position, wire 58, contacts 59—9, wire 60, pole changer coil 14, wires 61 and 48, fuse 25 back to the right-hand terminal of the secondary of transformer T^2 . This energization of the pole changer coil 14 while the track switch TS is unlocked causes the movable contact 7 to be operated to the opposite or reverse extreme position from that shown, thereby closing the normal operating circuit of the switch machine motor M and moving the track switch to its normal position.

However, considering that the reverse operation is to be completed, the switch machine continues to operate the track switch and lock it in its extreme reverse position.

When the track switch TS is locked in its reverse position, the movable contacts 7, 8 and 9 are operated by the switch machine to reverse extreme positions thereby opening the reverse operating circuit at contacts 44—7. In this connection, it is noted that preferably the movable contacts 8 and 9 are operated from intermediate positions to extreme positions slightly prior to the operation of movable contact 7. This provides that the movable contact 7 may be easily operated without undue mechanical stresses, as prior to its operation, the holding effect of the pole changer coil 12 or 14 is removed by the opening of its respective circuit at the contacts 54—8 or 59—9 respectively.

As soon as the operating circuit of the switch machine is opened at contacts 44—7 the current energizing the brake BR ceases to flow thereby causing the braking element to engage the motor armature A and immediately bring it to stop. It is to be understood in this connection, that the brake BR is included within the embodiment of the present invention more with the object of providing means for retaining the switch machine in

an operated position, than with an object of providing snubbing action which of course occurs when such a brake is provided. However, if the brake BR is omitted, the motor M inherently provides its own snubbing action by reason of the circulating currents produced in its own windings after external current supply is removed. These circulating currents are effective to absorb a part of any kinetic energy stored in the armature, which causes the armature to be brought to rest without undue over-run thereof.

One theory concerning this inherent snubbing action will now be briefly stated. With the motor energized as above described, the energizing circuit may be opened at any time during the time cycle of the alternating current supply, and at that time either the condenser or one of the phase windings, or the condenser and one or both of the phase windings will have energy stored therein. When the supply circuit is opened, this stored energy causes a current to oscillate back and forth between the condenser and the phase windings until the stored energy is dissipated in accordance with the phenomena of resonant circuits. The presence of this oscillating current in the phase windings produces a magnetic flux which is cut by the conductors of the armature windings, thus producing induced currents therein. Obviously, this production of induced currents in the armature absorbs a part of the kinetic energy stored in the armature.

The operation of the switch machine from a reverse position to a normal position will not be described in detail, as it may be readily understood by analogy to the operation already described. However, the normal operating circuit of the motor M is traced from the left-hand terminal of transformer T^2 , through fuse 24, wire 40, contact 18 of relay CR in a right-hand position, wires 58 and 62, contacts 63—7, wire 64, phase winding PH^2 , wire 46, winding of brake BR , wires 47 and 48, fuse 25, back to the right-hand terminal of transformer T^2 . During the normal operation, the condenser C is connected in series with phase winding PH^2 and this series combination, connected in multiple with phase winding PH^2 , receives current from the same source described for winding PH^2 .

It is noted, that during the normal operation, the current in the phase winding PH^2 is a lagging current with respect to current in PH' . This relative phase displacement is opposite from the phase displacement for the reverse operation above described, thereby causing the armature A to rotate in the opposite direction.

Let us now consider the characteristics of cross protection provided by the circuits and devices of the present invention, and the manner in which the application of either direct or alternating current through the various control wires is prevented from causing false and undesirable operations.

Let us first assume that a cross occurs between wires 30 and 36. If such a cross were to occur, the characteristic of current flow in the windings 15 and 16 of relay CR would be identical, that is, a pulsating alternating current with one-half of each cycle of considerably larger amplitude than the other half would be flowing in both windings. This larger amplitude alternates from one phase winding to the other winding but since the half cycles of the larger amplitude are substantially 180° out of phase with each other the resulting torque is substantially zero.

Let us now assume that a cross occurs between

wires 30 and 38', the transformer T^1 is thus short-circuited and no current flows to the relay CR to thus falsely control it. A similar condition exists when the control wires 36 and 38 are shorted 5 thereby shorting out the control relay CR and leaving only the rectifying unit R^3 in series with the transformer T^1 .

It is seen that, if an external alternating current source is applied to the wires 36 and 38, such 10 for example as from the transformer T^2 , no false control of the relay CR can occur, for the same reason given when the wires 30 and 36 were assumed to be connected.

If direct current is applied to the wires 36 and 15 38, no false control of the relay CR can occur inasmuch as it is an induction motor type relay and cannot respond to direct current.

Considering the operating circuits of the switch machine SM to be in normal conditions as shown, 20 a cross between the normal and reverse control wires 58 and 42 does not result in operation of the switch machine inasmuch as the motor M is shunted out by a circuit including contact 19 of relay CR. If such a cross occurs, a short circuit 25 on the transformer T^2 is traced from the left-hand terminal of the secondary of transformer T^2 , through fuse 24, wire 40, contact 18 of relay CR in a right-hand position, wire 58, through the cross to wire 42, contact 19 of relay CR in a 30 right-hand position, wire 65, fuse 25, to the right-hand terminal of the secondary of transformer T^2 . Such a short circuit on the transformer T^2 causes the fuses 24 and 25 to burn out thereby opening the circuit. If a cross occurs between 35 the wire 58 and wire 48, it is obvious that the same result occurs except that the short circuit on the transformer T^2 does not include the contact of relay CR.

It is noted that the motor M cannot respond 40 to any false application of direct current inasmuch as it is an alternating current induction type motor.

Thus, a control system for a railroad track switch has been shown and described, which is 45 accomplished entirely by the use of alternating current, this system being protected from crosses and being protected from the application of foreign alternating currents and foreign direct currents all in a manner that no false operation of the track switch can occur.

Having thus shown and described one particular embodiment of the present invention and having illustrated this embodiment in a rather conventional manner, it is desired to be understood that the simplified showing adopted for the disclosure of the present invention, has been selected for the purposes of facilitating in the description of the invention rather than for the specific purpose of showing the scope of the invention, and it is to be understood in this connection, that various changes, modifications and adaptations may be made to adapt the invention to the particular use to which it is desired to be put in a practical manner, all without departing 60 from the spirit or scope of the invention except as demanded by the scope of the following claims.

What I claim is:—

1. In a remote control system for railroad track switches, a manually operable control lever, a 70 remote track switch, a source of alternating current at said control lever, a source of alternating current at said track switch, means for operating said track switch from said source local there-

to, governing means for said operating means responsive only if uni-directional pulsating current is applied thereto, and means controlling said governing means including said control lever, said source local thereto and means at said lever for changing alternating current to uni-directional pulsating current, whereby said governing means and said operating means are protected from crosses between each other. 80

2. In a remote control system for railroad track switches, a manually operable control lever, a source of alternating current local to said lever, a remote track switch, a switch machine having a motor, a source of current local to said track switch, a relay for controlling the application of energy from said source local to said switch to said switch machine, said relay being of the induction two phase type having a rectifier connected in series combination with each phase winding, said rectifiers being oppositely poled in respect to each other, said series combinations being connected in multiple-series combination, a line circuit connecting said multiple-series combination of said relay with said control lever and said source local to said lever, and a rectifier in said line circuit at said lever, whereby said track switch may be operated to either of two opposite positions in accordance with said control lever. 85 90 95 100

3. In a remote control system for railroad track switches; a switch machine for operating the track switch; a manually operable control lever; a source of alternating current local to said control lever; a two phase induction motor type relay for controlling the operation of said switch machine, said relay having its two phase windings connected in multiple and including a rectifier means connected in series with each winding, and each rectifier means being poled oppositely and provided with a predetermined amount of leakage; a rectifier means associated with said control lever; and circuit means connecting in series said relay, said source, said rectifier means associated with said lever and said lever, whereby said rectifier means associated with said lever may be reversed in said series circuit when said lever is operated to an opposite position; whereby said relay is governable to either of two positions by said control lever resulting in a corresponding operation of said switch machine. 105 110 115 120 125

4. In a remote control system for railroad track switches; a switch machine for operating the track switch; a manually operable control lever; a source of alternating current local to said control lever; a two phase induction motor type relay 130 for controlling the operation of said switch machine, said relay having its two phase windings of like inductive characteristics connected in multiple and including a rectifier means connected in series with each winding, and each rectifier means being poled oppositely and provided with a predetermined amount of back leakage; a rectifier means associated with said control lever; and circuit means connecting in series said relay, said source, said rectifier means associated 135 with said lever and said lever, whereby said rectifier means associated with said lever may be reversed in said series circuit when said lever is operated to an opposite position; whereby said relay is governable to either of two positions by said control lever resulting in a corresponding operation of said switch machine. 140
